MOLD FOR CASTING A BRAKE HEAD

Francis M. Hess, Chicago, Ill., assignor to Chicago Railway Equipment Company, Chicago, Ill., a corporation of Illinois

Application October 16, 1939, Serial No. 299,601

6 Claims. (Cl. 22—131)

The invention relates to the production of railway brake beams and more particularly to the casting of brake heads associated with truss type beams.

5 It is common practice to use a cast brake head cored to receive one end of a compression member and to accommodate the passage therethrough of a tension rod having its end threaded for a tensioning nut which seats against an external face of the brake head and may be tightened to draw the parts together.

In casting brake heads of this type, difficulty is encountered in consistently placing the core accurately in the mold. The axis of the tension rod should be at the correct angle to the external face of the head for fully seating the nut. Any disalignment necessitates drilling and facing the casting; otherwise the useful life of the brake head and tension rod will be unduly limited.

20 One object of the invention is to insure a head casting in which the external face seating the tensioning nut will be at right angles to the axis of the passage for the tension rod.

Another object of the invention is to provide 25 a fixed angular relation between the tension nut receiving face and all internal surfaces of the brake head.

Another object of the invention is to provide 30 for casting a brake head with a rod receiving elongated sleeve in desired angular relation to the nut seating face.

Another object is to eliminate machine finishing of the brake head even though the core was 35 disaligned in the mold prior to the pouring of the metal or was floated out of correct position by the fluid metal.

These and other objects will appear in the specifications and from reference to the drawings in which—

40 Figure 1 is a top view of a truss type brake beam with one end portion sectioned horizontally.

Figure 2 is a vertical transverse section taken on the line 2—2 of Figure 1.

45 Figure 3 is a section through a portion of a mold and a core therein placed correctly to produce an accurate head casting which is also shown sectioned as it appears in Figure 1, but on a larger scale.

50 Figure 4 is a similar section but showing the head as produced when the core was shifted from its correct position before the metal was poured.

Figures 3 and 4 illustrate well-known mold, 55 core, and casting arrangements.

Figure 5 is a section corresponding generally to that shown in Figure 3 but embodying a core and mold arrangement embodying a form of the present invention.

60 Figure 6 is a section corresponding to that shown in Figure 5 but in which the core has been

shifted from its normal or correct position in the mold.

Figures 7 and 8 correspond to Figure 5 but illustrate other forms of the invention.

Figure 9 is a detail transverse section taken 5 on the line 9—9 of Figure 8.

The truss type brake beam illustrated in Figure 1 comprises a compression member 2, a tension rod 3, a strut 4, a pair of brake heads 5, seated on the ends of member 2, and nuts 6 10 threaded on the ends of rod 3 and seated against the outer faces of the compression member and holding the parts together and determining the initial tension on rod 3 and the camber of member 2.

Each brake head 5 is arranged to carry the usual brake shoe (not shown) and has a socket portion 11 which receives the end of compression member 2 and includes a bearing surface 12 for the tension rod and also includes an exterior 20 surface 13 at right angles to the axis of surface 12 and on which tension nut 6 seats.

In general practice socket portion 11 is formed by a baked sand core 14 which is positioned by core prints 15 and 16 which taper outwardly 25 and support the core from their seats in the green sand S of the mold. The green sand mold or matrix forms the exterior surfaces of the brake head and the baked sand core 14 forms the interior surfaces and when a head is cast 30 with the core placed correctly in the mold and a tension rod is placed against surface 12, the rod center line, as indicated at 17, will be at right angle to the head exterior surface 13 and the rod nut 6 will then fully seat as indicated 35 by the dotted line 18 in Figure 3.

In the hurry of production, molders are sometimes careless and place the core in a disaligned position relative to the pattern print, as illustrated in Figure 4, and this will shift all interior surfaces, including the tension rod bearing 12, 40 relative to the exterior surfaces, and when the head is assembled with the other beam parts, the nut will seat against the surface 13 at only one point, as indicated by dotted line 19 in Figure 4. A burr, indicated at 20, may be formed 45 by the tapered core print 16 shifting into the pattern print. This would prevent a full contact of the rod with the bearing 12.

Before such a misformed casting can be used, the burr 20 must be removed and the surface 50 13 must be faced so that nut 6 will fully seat and the tension rod will contact the full length of surface 12.

Figures 5 and 6 illustrate an arrangement of 55 mold and core whereby all interior surfaces of the head will be in fixed relation to the surface seating the tensioning nut. Core 26 is provided with an enlarged core print 27 to rest in the green sand to support the core and having an annular face 27a spaced from the core shoulder 60

28 and forming the portion of the mold which produces the nut seat 29 on the head. The rod bearing forming side 30 of the core extends sufficiently to form a portion of the core print 31 so that no burrs are formed if the core is disaligned in the mold.

5 Forming the exterior nut seating surface 29 by the core eliminates the expensive operation of drilling and facing the casting to obtain the 10 desired angle between the tension rod bearing 32 and the nut bearing surface 29. Also surfaces 33 that position the compression member are in fixed relation to the surface 29 irrespective of the position core 26 assumes in the mold.

15 Another arrangement is illustrated in Figure 7 in which a short tension rod receiving sleeve 34 in the head 35 is formed by the core 36. The core print 37 forms the external tension nut seat in fixed relation to the center line 38 of the 20 sleeve 34. Core prints 39 and 40 are of such length that burrs will not be formed on the casting if the core print is shifted in the pattern print.

25 Another arrangement is illustrated in Figures 8 and 9 in which a full length tension rod receiving sleeve 45 is formed in the head by the one-piece core 47. The sleeve-coring portion 48 is supported by the ribs 49 which form slots in the sleeve, but do not affect the efficiency of 30 the sleeve. The enlarged core print 50 forms the tension nut bearing face 51 in fixed relation to the center line 52 of sleeve 45.

35 In all forms of the invention illustrated, one exterior nut-bearing surface is formed by the core and accordingly is in fixed angular relation to all interior surfaces of the brake head socket portion irrespective of the core shifting relative to the pattern print. The advantage of this relation is particularly marked in the arrangements shown in Figures 7 and 8 in which the 40 heads include sleeves for surrounding the rod.

45 While the structures described are particularly adaptable for casting railway brake heads which have bearings for the side of the rod at points spaced from the nut, it is to be understood that 50 the correct positioning of the nut seat is not dependent upon this feature and variations in the head other than the one shown may be made by those skilled in the art without departing from the spirit of the invention, and the exclusive use of such modifications as come within the scope of the claims is contemplated.

55 What is claimed is:

1. In a mold for a railway brake head, a green sand matrix including a core supporting print and a surface for shaping the exterior of the casting, and a one piece core of baked sand having a print supported in said matrix print, said core print including a portion forming an extension of said matrix surface for shaping the exterior of the casting part which seats the tension rod nut, said core having a portion for shaping an interior surface of the casting which seats the side of the tension rod.

60 2. A core for a railway brake head forming 65 mold, comprising a body part for shaping the interior of the brake head and providing thereon a surface forming a bearing for the side of a tension rod, and a print projecting from said body part to support the core in the mold and 70 having a portion facing toward said body part for shaping an exterior surface of the brake head and providing thereon a seat for a tension nut

threaded on the rod whereby said bearing and said seat will be cast in a predetermined relation to each other irrespective of variation in the mold matrix or variation in the relative position of the core in the mold matrix.

5 3. A one-piece rigid core for use in casting a railway brake beam head and comprising a cylindrical portion arranged to form the inner wall of a cylindrical sleeve extending inwardly from the side wall of the head, for receiving a 10 brake beam tension rod, and a flat annular portion extending transversely of the axis of said cylindrical portion and arranged to form an outwardly facing seat for a nut threaded on a beam tension rod inserted through said sleeve.

15 4. In a mold for casting a railway brake head having a cylindrical sleeve extending inwardly from one side thereof, a green sand matrix including a core supporting print and a surface for shaping the exterior of the casting, and a one-piece core of baked sand having a print supported in said matrix print, said core print including a portion forming an extension of said matrix surface for shaping the exterior of the casting part which is adapted to seat a tension 25 rod nut, said core having a cylindrical portion arranged to form the inner wall of the head cylindrical sleeve, said nut seat forming portion being disposed at right angles to the axis of said cylindrical portion whereby the relation between 30 the nut seat and the rod receiving portion of the cast head will be determined irrespective of variation in the mold matrix or variation in the relative position of the core in the mold matrix.

35 5. A one-piece rigid core for use in casting a railway brake beam head having a sleeve extending between its side walls, comprising spaced body portions shaped to form inner walls of the head, a cylindrical portion intermediate said body portions and arranged to form the inner wall of a 40 cylindrical sleeve extending from side to side of the head, there being ribs of restricted cross sectional area between said cylindrical portion and said body portions, and a flat annular portion extending from said cylindrical portion transversely of the axis of the latter to form an outwardly facing seat for a nut threaded on a beam tension rod extending through said sleeve, whereby the angle between said nut seat and the rod extending through said sleeve may be predetermined irrespective of variation in the mold matrix or of the position of the core in the mold matrix.

45 6. In a mold for a railway brake head having a cylindrical sleeve extending from one side to 55 the other, a green sand matrix including a core supporting print at one side and a surface for shaping the exterior of the casting, and a one-piece core of baked sand having a print supported in said matrix print and including a portion forming an extension of said matrix surface for shaping the exterior of the casting part to seat a beam tension rod nut, said core having a cylindrical portion extending to the opposite side of said matrix and arranged to form the inner wall of a cylindrical sleeve in the casting, whereby the relation between said seat and the axis of a rod extending through said sleeve may be predetermined irrespective of variation in the mold matrix or variation in the position of the core in 60 said matrix.
